UNITED STATES PATENT OFFICE.

NIELS B. JANSSEN, OF KANSAS CITY, MISSOURI.

CONVEYING AND CLEANING TABLE.

1,253,495.

Specification of Letters Patent. Patented Jan. 15, 1918.

Application filed October 30, 1916. Serial No. 128,431.

To all whom it may concern:

Be it known that I, NIELS B. JANSSEN, a citizen of the United States, residing at Kansas City, in the county of Jackson and State of Missouri, have invented certain new and useful Improvements in Conveying and Cleaning Tables; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to conveying and cleaning tables, and more particularly to a table for facilitating the cleaning, and grading of celery or the like, the principal object of the invention being to provide a table of this character comprising movable sections whereon the celery is assorted, cleaned and graded, and which may be interchanged between workmen who do the separate phases of the work, so that the work is greatly facilitated and accomplished without confusion among the workers and particularly without bruising or damaging the plants.

A further object of the invention is to provide simple and easily operated means for interchanging the sections or tables between the workmen.

In accomplishing these objects I have provided improved details of structure, the preferred forms of which are illustrated in the accompanying drawings, wherein:

Figure I is a perspective view of a cleaning and assorting table constructed according to my invention.

Fig. II is a longitudinal vertical section of the same, showing the movable sections.

Fig. III is a transverse vertical section on the line III—III, Fig. II.

Fig. IV is a transverse section on the line IV—IV, Fig. II showing the relative positions of the tracks for interchanging the sections.

Fig. V is a perspective view of the table supporting tracks, illustrating the lowering and raising devices.

Fig. VI is a detail perspective view of the hinge mounting of one of the tracks.

Referring more in detail to the drawings:

1 designates a cleaning and grading table constructed according to my invention, comprising a frame 2, which may be made in lengths to accommodate a desired number of workmen, and having opposite side members 3—3', ends 4—4', and supporting legs 5.

Mounted within the frame between the sides 3—3', and slightly below the top level thereof, are tables 6—6', each of which is of approximately one-half the length of the frame 2, and is removably mounted so that the tables may be interchanged as the work progresses.

Attached to the under side of each of the tables by journals 7 are axles 8 carrying 70 rollers 9, whereby the tables are supported on tracks 10—10' that are carried by and project inwardly from the sides of and extend throughout the length of the frame.

In order that the tables may be interchanged, the track 10, which comprises rails 11—11' and the tie rods 12, is pivotally mounted adjacent its outer end on brackets 13 that are attached to the side frame members 3—3' and is supported at its free end 80 by the cross bar 14 of a crank 15, comprising side arms 16—16' and outturned bearing portions 17—17' which are pivotally mounted in the side beams 3—3', the crank being provided, externally of the frame and at one 85 side thereof, with a lever 18 whereby the crank 15 may be moved to raise the free end of the track 10 and support the same in horizontal position and in coextension with the track 10', or to lower the free end to a 90 level with sub-tracks 19—19' that are supported in the frame below the track 10'.

In order to retain the track 10 normally in horizontal position, I provide a support 20 for the lever 18, which is attached to the 95 lower edge of the side rail 3, and so form the crank bar that when the lever is seated on the support 20 the cross bar 14 on which the track rests is positioned slightly back of the pivotal point of the crank, so that in 100 lowering the track, the bar 14 must be moved back over the dead center position.

The track 19, which is located below the track 10', comprises spaced rails 21—21' that are joined by the end tie rods 22—22', 105 and when in normal position rests on cross

bars 23—23' that extend transversely between the side frames 3—3', and is a continuation of the track rails 19' which are permanently mounted on the bars 23—23', so that when the free end of the track 10 is lowered by operation of the lever 18, a table 6 carried thereon may be moved onto the tracks 19' and 19 to a position beneath the table 6'.

10 Pivots mounted in the frame sides 3—3' adjacent opposite ends of the track 19 are crank members 25—25', comprising cross bars 26—26' on which the track rails are pivotally mounted, and side arms 27—27' which are turned laterally at their ends to form bearing portions 28—28' which are pivotally mounted in the sides 3—3'; the said cranks being provided at the exterior of the frame with levers 29—29' that are pivotally connected at their ends by a link 30. Also pivotally connected with the lever 29 is a link 31 which extends to a lever 32, pivotally mounted on the frame side 3, so that by moving the lever 32, the crank levers 25—25' will be rocked on their pivotal mounting to raise the track 19 from its supports to a position substantially level with the track 10.

15 The track 10' comprises the side rails 10' preferably of angle iron construction and each hingedly mounted on the frame sides 3—3', so that the rails may lie in position to support the tables 6—6' or may be tilted outwardly on their hinged mounts to permit the passage of a table, that may be supported on the track 19 therebetween when the latter is raised by operation of the lever 32.

20 In the present device I prefer to cut away a portion of the front frame 3 above the level 40 of the table 6 to permit the graded product to be more easily removed from the tables after it has been washed. I also prefer to form the tables of spaced slats so that water or dirt removed from the plants may fall 45 therebetween to beneath the table, in order that the plants may be kept free from dirt.

25 Assuming the parts to be so constructed, in using the device, the tables 6—6' are raised to position on the tracks 10—10'. The uncleared celery is first placed on the table 6' where the roots and leaves may be removed and the plants washed. The table 6' is then moved along the track 10' onto the track 10 to the position previously occupied by the table 6 which in the meantime has been moved to the track 19.

30 To lower the table 6 from the track 10 to track 19 below the table 6', the operator moves the lever 18 to revolve the crank 15 in its mounting so that the cross bar 14 is lowered and the track inclined downwardly to the level of the track 19, permitting the table 6 to be rolled from the track to position beneath the table 6'. The track 10 is then raised to normal horizontal position

35 and locked by moving the lever 18 back to seat against the supporting arm 20.

40 After the table of cleaned and trimmed celery has been moved onto the track 10 into position for the workmen who do the grading, the table 6 is raised onto the track 10' to receive the uncleared product.

45 To raise the lower table to the initial position, the operator moves the lever 32 rearwardly to revolve the crank levers 25—25' in 75 their mountings and thereby raise the track 19 with the table thereon between the track rails 35—35'; the latter tilting outwardly on the hinged mountings to permit the passage of the table therebetween, but falling 80 back to catch the table as soon as it has been sufficiently raised.

50 By so constructing the table and tracks, it will be seen that the work of cleaning and assorting may be carried on by separate 85 groups of workmen without confusion and without their changing positions, thereby greatly facilitating the work, moreover, the work may all be accomplished without sliding or moving the plants along the table, 90 and thereby eliminate all friction, which would be apt to cause bruising of the plants.

55 Having thus described my invention what I claim as new therein and desire to secure by Letters Patent, is:

60 1. A conveying and cleaning table comprising separate coextensive track sections, tables movable on said sections, and means for interchanging the tables on the separate sections.

65 2. A conveying and cleaning table comprising separate coextensive and independently movable track sections, tables adapted for support on the track sections, and means for shifting the tables from one to another 105 of said sections.

70 3. A conveying and cleaning table comprising a frame, upper and lower tracks mounted in said frame, and means for moving said tables along said tracks to interchange their positions thereon.

75 4. A conveying and cleaning table comprising a frame, upper track sections and a lower track, tables adapted for rolling on said tracks, and means for moving one of the upper track sections to co-operative relation with the lower track, for the purpose set forth.

80 5. A conveying and cleaning table comprising coextensive track sections, one yieldable vertically to permit passage of a table between its rails from beneath the track level, and an elevator for positioning a table on the yieldable track.

85 6. A conveying and cleaning table comprising coextensive track sections, one yieldable vertically to permit passage of a table between its rails from beneath the track level, an elevator for positioning a table on the yieldable track, and means for conduct-

ing a table from the other track section to said elevator.

7. In a conveying and cleaning table, a track comprising rails having longitudinal, pivotal mounting, a track normally coextensive with the first named track, and having transverse pivotal mounting, tables movable on said tracks, and an elevator for receiving a table from one of the tracks and conducting the same to the other track.

8. A conveying and cleaning table com-

prising a frame, upper track sections forming a continuous track longitudinally of said frame, a lower track, tables movably mounted on said tracks, means for moving one of the upper track sections to coöperative relation with the lower track, and means for raising the lower track to coöperative relation with the upper track section, for the purpose set forth.

20 In testimony whereof I affix my signature.

NIELS B. JANSSEN.
